PRESSURE COOKER COVER SUPPORT

Myron J. Zimmer, Wood Dale, Ill., assignor to
Ekco Products Company, Chicago, Ill., a cor-
poration of Illinois

Application October 29, 1947, Serial No. 782,711

2 Claims. (Cl. 220—25)

1

The invention relates generally to pressure cookers and more particularly to the manner of supporting the cover thereof.

One type of pressure cooker adapted for home use comprises a receptacle having an elliptical opening, with the cover adapted to be inserted within the receptacle and to engage the underside of the margin of the elliptical opening for sealing the receptacle. To remove the cover for access to the receptacle, the former is rotated 90° out of alignment with the opening and then tilted for withdrawal upwardly through the opening. When the cover is in place, it is supported from a bridge member spanning the opening in the receptacle and seated at its ends on the receptacle or on the handles thereof. The bridge member is held against rotation, and a knob may be provided for rotating the cover, the knob being mounted on the bridge member and being connected to the cover by means such as a stem. In this type of construction, means operable by the knob, or in some instances a spring, may be employed for raising the cover into engagement with the underside of the margin of the opening when the opening and cover are aligned.

With a cover structure of this type, the cover need be held in engagement with the margin of the opening only sufficiently to permit the pressure to start building up within the receptacle. The pressure itself thereafter holds the cover in sealing engagement with the margin. However, it has been found that, unless the cover is in fairly true axial alignment with the opening, or in other words, in coplanar relation with the margin thereof, the cover may not engage the margin at all points and leakage of pressure occurs so that the building up of pressure does not occur. Such lack of axial alignment of the cover and opening may occur in manufacturing or may result from misuse. Thus, the cover might have a slight warp, or it might not be secured to the stem in true axial alignment, or the stem might be held slightly out of axial alignment with the opening under the pressure of the spring. Any of these difficulties might cause the cover to engage the margin of the opening only through a portion of its periphery, leaving an unsealed portion through which steam could escape. Pressure would, therefore, not be attained within the receptacle.

The general object of the invention is, therefore, to provide a cover support for a pressure cooker of the foregoing type, which permits the cover to engage the margin of the receptacle opening in substantially true coaxial alignment

or coplanar engagement, so that a sealing relation of the cover with the margin is established.

Another object is to provide a cover support which permits the cover to be self-adjusting to the margin of the receptacle opening to effect a seal therewith so that pressure may be built up within the receptacle.

A further object is to provide a cover support having the foregoing features and which may be readily manufactured without requiring a high degree of accuracy in making the parts or assembling them.

Other objects and advantages will become apparent from the following description taken in connection with the accompanying drawings, in which:

Figure 1 is a fragmentary vertical sectional view through a pressure cooker having a cover support embodying the features of the invention, the figure showing the cover in its closed position.

Fig. 2 is an enlarged fragmentary sectional view taken on the line 2—2 of Fig. 1.

In pressure cookers of the above type employing a knob for rotating the cover into and out of alignment with the receptacle opening and having a spring for raising the cover when taken into aligned position, the knob is manually depressed to compress the spring when it is desired to lower the cover and turn it out of alignment. In this type of construction, a lock is employed for holding the cover depressed when out of alignment with the opening, so that the cover and bridge member may be more easily manipulated. The spring for raising the cover, in this type of construction, should not be too stiff because a stiff spring makes it difficult for the user to depress the cover. On the other hand, a stiff spring is desirable in moving the cover upwardly in order to force the cover into proper engagement with the margin of the opening in the receptacle.

In some construction, the knob for turning the cover may be released from the cover when the latter is turned to its aligned position, and, by further turning movement, effect a slight upward movement of the cover in addition to that required to raise it from its lower position to a position where it contacts the margin. Such further raising of the cover insures tight engagement thereof with the margin of the receptacle opening and thus definitely establishes a seal therebetween. The mechanism for effecting such operation, however, is usually somewhat complicat-

ed and necessarily increases the cost of manufacture.

The present invention provides a structure which permits the cover to readily engage the margin of the opening throughout the entire circumference without the necessity of applying a large force thereto. Thus, in the case of a cooker having a spring for elevating the cover, the spring may be such that it can be easily manipulated by the user in moving the cover out of contact with the margin of the opening. In the case of the construction where the knob has an extra turning movement to definitely bring the cover up into sealing engagement with the margin of the opening, the present structure insures proper contact of the cover with the margin. In other words, the present structure permits the cover to adjust itself into axial alignment with the opening in the receptacle so that the cover and margin of the opening are in coplanar relation.

To illustrate the invention, it is embodied in a cooker of the type in which a spring is utilized for raising the cover into engagement with the margin of the receptacle opening. However, as mentioned above, the invention is not limited to the use of such a spring but is of benefit in other cookers as described. In the drawing, the cooker is shown as comprising a receptacle fragmentarily indicated at 10, and a cover 11. The receptacle 10 is provided at its top with an inwardly turned flange 12 providing an opening 13 which is elliptical in form. The cover 11 has a downwardly directed portion 14 and an outwardly turned flange 15 with a lip 16 at the outer edge thereof providing a peripheral channel in which a gasket 17 is mounted. The gasket 17 is of rubber or other resilient material and is adapted, when the cover is in its closed position in the receptacle, to contact the underside of the flange 12 at the margin of the opening 13.

Spanning the opening 13 is a bridge member 20 which is somewhat bowed in form and has its ends seated in pockets 21 adjacent the periphery of the receptacle 10. In the present instance, the pockets 21 are formed in handles 22 for the receptacle 10. The bridge member 20 provides a means by which the cover 11 may be suspended for rotation and for vertical movement. To this end, a stem 23 is provided which, at its lower end, is connected to the cover in a manner hereinafter described. The structure for operating the stem is of the character shown in my copending application, Serial No. 598,725, filed June 11, 1945, Patent No. 2,531,717, November 28, 1950. In this structure, the stem 23 is provided at its upper end with an enlarged portion 24 having an axially positioned threaded hole 25 in its upper end. Mounted on the stem is a hollow knob 26 secured thereto by a screw 27 extending into the threaded hole 25. The knob 26 is preferably made of heat-insulating material so that it may be readily grasped without burning the user's hand, and is provided with a metal liner 30 which is also secured to the upper end of the stem 24.

Rigidly mounted on the bridge member 20 is a cup-shaped member 31 which, at its lower end, extends through an aperture 32 in the bridge member and provides a bearing for the stem 23. Surrounding the stem 23 is a coil spring 33 bearing at its lower end against the cup-shaped member 31 and at its upper end against the metal liner 30 for the knob 26. The spring 33 thus tends to urge the cover upwardly relative to the bridge member 20 and, consequently, tends to

move the cover into engagement at its periphery with the margin of the opening 13 in the receptacle. To lower the cover out of contact with the margin of the opening the knob 26 may be depressed against the pressure of the spring 33. To facilitate manipulation of the cover, the cup-shaped member 31 and the liner 30 are provided with interlocking portions, indicated at 34, for holding the cover in a depressed position, such interlocking portions forming no part of the present invention but being fully disclosed in my above-mentioned copending application.

Since the spring 33 has to be compressed manually by pushing down on the knob 26 in order to move the cover out of engagement with the margin of the opening 13, it is desirable that the spring 33 be such that it does not require a large force to compress it to the extent necessary for lowering the cover. However, should the cover 20 be slightly warped or should it be out of true axial alignment with the stem 23 or out of axial alignment with the opening 13 so that it is canted slightly relative to such opening, a seal will not be established between the gasket 17 on the cover 20 and the flange 12 of the receptacle. If the spring 33 is light enough to permit easy manipulation, as described above, it does not exert sufficient force to correct slight misalignments of the cover with the opening 13. The connection between the stem 23 and the cover is, therefore, such that the cover, when drawn upwardly, even under a relatively light force, will adjust itself relative to the flange 12 of the receptacle and will tend to contact such flange throughout the entire circumference of the opening. In the present instance, the connection between the stem 23 and the cover 11 is of the nature of a universal joint which permits the cover to tilt slightly in any direction relative to the stem 23. Thus, when the cover is drawn upwardly by the spring 33, it will be moved into coplanar relation with the flange 12 by the force of the spring and the permissible tilting movement of the cover, so that a tight sealing engagement between the gasket 17 and the flange 12 is thereby effected. Such engagement is sufficient to start the building up of pressure when heat is applied to the receptacle.

To provide such a universal connection, the cover 11 is preferably depressed as at 40 in its central portion. Mounted in the depression 40 is a stem-receiving member, indicated generally at 41, and comprising a flange 42 seated in the depression 40 and secured to the cover as by welding. The stem-receiving member also has a tubular portion 43 providing a socket 44 in which the lower end of the stem 23 loosely fits. To connect the stem 23 to the member 41, a pivotal connection is provided comprising, in the present instance, a pin 45 rigidly secured in the lower end of the stem 23 in diametrical position therein and extending at both ends beyond the stem. The tubular portion 43 of the member 41 is provided with a pair of diametrically aligned apertures 46 which loosely receive the ends of the pin 45.

The cover 11 is thus permitted to tilt slightly relative to the stem 23 in any direction because of the loose fit of the stem within the tubular portion 43 and the loose fit of the ends of the pin 45 in the apertures 46. To hold the stem and cover 20 normally aligned, a coil spring 47 may be mounted within the tubular portion 43 to bear at one end against the depressed portion of the cover 11 and at the other end against the lower end of the stem 23. The spring 47 thus tends to force the stem 23 upwardly within the tubular portion 43 to hold

the stem and cover in alignment. However, when the gasket 17 at the periphery of the cover engages the flange 12 at any point, the cover may tilt freely to the extent necessary to bring it into coplanar relation with the flange 12. The cover is thus enabled to effect a tight engagement with the flange, sufficient to prevent release of steam so that pressure will build up within the receptacle. The pressure itself, of course, after it is once established, will tend to hold the cover in proper engagement with the flange of the receptacle.

I claim:

1. In a pressure cooker comprising a receptacle having an elliptical top opening and a cover, with the cover engageable with the underside of the margin of said opening and movable therethrough when tilted and rotated 90° out of alignment with said opening, the combination of a bridge member adapted to be seated at its ends on the receptacle over said opening and to be held against rotation relative thereto when so seated, a cover-supporting stem for rotating the cover and moving it vertically, said stem extending through said bridge member for rotation and axial movement therein, means mounted on said bridge member and connected to said stem for rotating the cover into and out of alignment with said opening and for raising and lowering the cover into and out of engagement with the margin thereof including a manually rotatable knob positioned centrally over said bridge member and coaxial with said stem, a universal connection between said cover and said stem to permit the cover to tilt relative to the stem into coplanar relation with the margin of said opening when the cover is raised by said means into engagement with the margin, and a spring interposed between said cover and said stem and tending to hold said cover coaxial with said stem.

2. In a pressure cooker comprising a receptacle having an elliptical top opening and a cover, with the cover engageable with the underside of the margin of said opening and movable therethrough when tilted and rotated 90° out of alignment with said opening, the combination of a bridge member adapted to be seated at its ends on

the receptacle over said opening and to be held against rotation relative thereto when so seated, a cover-supporting stem for rotating the cover and moving it vertically, said stem extending through said bridge member for rotation and axial movement therein, means mounted on said bridge member and connected to said stem for rotating the cover into and out of alignment with said opening and for raising and lowering the cover into and out of engagement with the margin thereof including a manually rotatable knob positioned centrally over said bridge member and coaxial with said stem, and a universal connection between said cover and said stem comprising a socket member rigid with the cover and having an upstanding tubular portion loosely receiving the lower end of said stem, said tubular portion having a pair of diametrically opposite holes, a pin extending through said stem and loosely received at its ends in said holes to permit the cover to tilt to a limited extent relative to the stem, and a spring in said socket member interposed between said cover and said stem and tending to hold them in axial alignment.
